[57] ABSTRACT

Water free solutions of percarboxylic acids having two to four carbon atoms are prepared by extracting aqueous solutions of the percarboxylic acids with phosphate esters having three to 30 carbon atoms, desorbing the extract with a solvent and dehydrating the solvent, in a given case by azeotropic distillation, if necessary after addition of a carboxylic acid ester boiling below the percarboxylic acid.

16 Claims, No Drawings

PROCESS FOR THE PRODUCTION OF ORGANIC SOLUTIONS OF PERCARBOXYLIC ACIDS

The present invention is concerned with a process for the production of water free solutions of percarboxylic acids having two to four carbon atoms.

The production of water free solutions of percarboxylic acids, especially peracetic acid is known and is described in the following articles:

Ullmann, Encycl. d. techn. Chemie Erg. Vol., 1970, Neve Verfahren, pages 181 et seq., Urban and Schwarzenberg, Munich;

Kirk-Othmer, Encyclopedia of Chemical Technology, first edition, first Supplement Volume, pages 622 et seq., Interscience, New York, 1957;

Swern, Organic Peroxides, Vol. I, page 313 et seq., Wiley-Interscience, New York, 1970.

The production of organic percarboxylic acid solutions by known processes is uneconomical in industrial operation because in order to guarantee safety an unusually high expenditure is necessary for regulating and safety devices. In the production of percarboxylic acids from hydrogen peroxide and carboxylic acids in the presence of organo solvents and water therefore care must be taken that once the reaction has completely terminated, namely by removal of the water, on the other hand there is not allowed to occur a concentration of the percarboxylic acid in organic solvents which cause explosive mixtures to form. Therefore in the processing of peroxy compounds the process conditions are adhered to very exactly because slight deviations lead to the formation of mixtures capable of explosion. Water free solutions are formed to be sure directly by oxidation of aldehydes which process can be carried out in either the liquid or the gas phase. However, in this process there are formed on the one hand extraordinarily dangerous intermediate products and on the other hand there accumulates after the reaction of the percarboxylic acid the corresponding carboxylic acids as byproducts which is exceedingly undesirable.

In the known methods of production the organic solutions stand for a long time, in part at elevated temperature, and under drastic chemical conditions which are provided by the presence of acid catalysts with hydrogen peroxide and percarboxylic acids in contact whereby the breakdown of the solvent with formation of disturbing byproducts is favored.

The present process was developed to avoid these disadvantages. In the present process organic solvents are added for the first time after the end of the formation of the percarboxylic acid, wherein, in comparison to the known processes, a simple and safe reaction procedure as well as a reduction in decomposition of the organic solvent is achieved.

It has now been found that organic percarboxylic acid solutions can be produced safely if aqueous solutions of percarboxylic acids having two to four carbon atoms, specifically the peralkanoic acids, peracetic acids, perpropionic acid, perisobutyric acid and perbutyric acid, are extracted with organic phosphates having three to 30 carbon atoms whereupon the extract is desorbed with an organic solvent, preferably an ester of a carboxylic acid having four to 10 carbon atoms, e.g., an alkyl alkanoate, and the desorbate of percarboxylic acid and solvent dehydrated, in a given case by azeotropic distillation, if necessary after addition of a

carboxylic acid ester boiling below the percarboxylic acid.

In this manner there are obtained the desired organic solutions of percarboxylic acids in a simple and economical manner.

As aqueous solutions of percarboxylic acids there are preferably employed those prepared by German Pat. Nos. 1,165,576 and 1,170,926. The entire disclosure of these two German patents is hereby incorporated by reference. The concentration of the aqueous percarboxylic acid can be between 10 and 80 percent, preferably 20 to 60 percent.

Unless otherwise indicated all parts and percentages are by weight.

15 As phosphate esters there can be employed tertiary phosphates of the formula

20

where R₁, R₂ and R₃ are the same or different and are alkyl, aryl or aralkyl and have a total of three to 30 carbon atoms.

25

Examples of suitable extraction agents are trimethyl phosphate, tributyl phosphate, trioctyl phosphates, dioctylphenyl phosphate, triethyl phosphate, tripropyl phosphate, triisobutyl phosphate, triamyl phosphate, trihexyl phosphate, tricyclohexyl phosphate, triisooctyl phosphate, tri 2-ethylhexyl phosphate, triisodecyl phosphate, tri decyl phosphate, diphenyl isodecyl phosphate, diisodecyl phenyl phosphate, triphenyl phosphate, tricresyl phosphate, diphenyl cresyl phosphate, dimethyl phenyl phosphate, tribenzyl phosphate. Especially suited are trimethyl phosphate, tributyl phosphate and trioctyl phosphate. Of course there can be employed mixtures of phosphate esters.

30

As desorbents there can be used alkyl alkanoates such as ethyl acetate, propyl acetate, butyl acetate, amyl acetate, 2-ethylhexyl acetate, cyclohexyl acetate, t-butyl acetate, isoamyl acetate, propyl formate, butyl formate, methyl propionate, ethyl propionate, methyl butyrate, ethyl butyrate, methyl valerate, sec-hexyl acetate, propyl propionate, butyl propionate, amyl propionate, methyl isobutyrate, ethyl valerate, propyl isovalerate, methyl caproate, methyl pivalate, ethyl pivalate, propyl pivalate, isopropyl pivalate, butyl pivalate, sec-butyl pivalate and amyl pivalate. Other desorbents are mentioned later in the specification.

35

The esters employed to aid in the dehydration can be the same as those set forth above so long as they boil below the percarboxylic acid.

40

The extraction is preferably carried out continuously, best by countercurrent operation, namely in conventional extraction apparatus such as for example extraction columns with plates or packing with or without pulsation. As packing there can suitably be added rings, saddles or helices. As plates there can be used perforated plates, tunnel plates or bubble trays.

45

The aqueous percarboxylic acid is fed below the top of the column and the phosphate ester at the lower end of the column. A largely water free solution of percarboxylic acid is drawn off at the top of the column while the raffinate which contains negligibly small amounts of active oxygen is withdrawn from the lower end. The amount of ester used is determined by special solvent

loading curve and by the required concentration of percarboxylic acid.

To desorb the percarboxylic acid the extract is fed to a thin film evaporator, preferably with moving inner parts, operating in a vacuum. Simultaneously the necessary amount of solvent is supplied to the evaporator, wherein a portion of the solvent is fed to the lower end of the evaporator in vapor form. The amount of solvent is determined likewise by the required concentration of percarboxylic acid.

By condensation of the desorbate water containing percarboxylic acid solutions in organic solvents are obtained. For many purposes the water content of the solution, e.g., does not play a disturbing role so that the organic percarboxylic acid solution is usable directly without a previous azeotropic distillation.

If water free organic percarboxylic acids are required the desorbate is preferably fed to a continuously operating distillation plant which is provided at the top with a separator for the water taken off while the percarboxylic acid solution is drawn off at the sump.

If a carboxylic acid ester having a higher boiling point than the percarboxylic acid is used for the desorption then there must be added to the desorbate a carboxylic acid ester having a lower boiling point than the percarboxylic acid. The carboxylic acid ester is so selected that only slight amounts of the percarboxylic acid distill

rene, toluene, xylene, and ethyl benzene or mixtures of such solvents. Preferably there are used, however, carboxylic acid esters containing four to 10 carbon atoms or mixtures containing them.

5 The concentration of the organic solvent percarboxylic acid solution on the lower side is determined by industrial considerations and on the upper side by the danger motive. The solutions therefore can contain a concentration of 10 to 60 percent, preferably 20 to 50 percent of the percarboxylic acid.

10 The extraction can be operated at normal pressure at temperatures of 5° to 50°C., preferably at 10° to 30°C. The azeotropic dehydration and desorption are carried out in a vacuum at 20 to 400 Torr, preferably 50 to 250

15 Torr. The sump temperature is 40° to 100°C., preferably 50° to 80°C.

The invention is further explained by the following examples.

EXAMPLES

20 A. Apparatus Employed: The extraction unit with the necessary equipment consisted of a tube 2 meters long and having a diameter of 2.8 cm in which there were located 40 screens having a hole diameter of 1 mm. The column was pulsated with a pulsation pump and operated in countercurrent manner. The results of the extraction experiments are set forth in the following examples.

25

Example	Extraction Agent	Vol Ratio 55-59% PES Extraction Agent	PES Content in g/l		Water Content Organic Phase g/l	% PES vs. Amount Added in the Extract
			Organic Phase	Water Phase		
1	tributyl phosphate	1:2.72	178	1.7	45.4	99.9
2	tributyl phosphate	1:1.36	291	9.2	55.4	99.2
3	trioctyl phosphate	1:3.07	167	64.5	13.1	97.3
4	trioctyl phosphate	1:5.93	98	4.0	12.0	99.8

PES = peracetic acid.

off from the desorbate together with the water and entraining agent. Thereby there is safely prevented the build up of dangerously high percarboxylic acid concentrations in the column and the boiling point of the mixture is reduced. The amount of lower boiling ester can be determined by one skilled in the art by a simple preliminary test.

45 For the desorption there can be used all organic solvents which are lower boiling than the phosphate esters, for example carboxylic acid esters such as those set forth above, chlorinated hydrocarbons, e.g., carbon tetrachloride, chloroform, ethylene dichloride, acetylene tetrachloride, ethylene trichloride, 1,2-dichloroethylene, aromatic hydrocarbons, e.g., ben-

The other peracids, e.g., perpropionic acid and perisobutyric acid can be extracted with equally good success. The yield of active oxygen and the purity of the product in such cases corresponds to that with peracetic acid.

50 B. Desorption Apparatus: For desorption the extract from the extraction unit described above was fed into thin film evaporator having internal moving parts and operating in a vacuum. Simultaneously with the extract there were fed to the evaporator a solvent for desorption, partially in liquid form and partially in vapor form at the lower end of the thin layer evaporator.

55 Examples B₁-B₃ in the following table show the results of the tests with peracetic acid:

Example B	PES Extracted In	Added Solvent	Volume Ratio Extract Solvent	PES Content		Water Content in g/l	% PES vs. added in the Distillation
				Extract Added	Product		
1	tributyl phosphate	n-butyl acetate	1.05:1	291	230	55.4	42.4
2	trioctyl phosphate	n-butyl acetate	2.17:1	164	263	12.4	19.4
3	trioctyl phosphate	ethyl acetate	2.17:1	164	284	12.4	not observed

PES = peracetic acid
General Conditions:

pressure = 50 Torr
Evaporator temperature = 100°C.
Transition temperature at the evaporator: 50-55°C.

Just as in the extraction good results are obtained where perpropionic acid or perisobutyric acid is employed in the desorption. The desorbate obtained can be either condensed and further used as such or left in liquid or vapor form to a dehydration unit which consists essentially of an azeotropic distillation operating in a vacuum. According to Example C the desorbate was directly dehydrated while there was added to the desorbate from n-butyl acetate and peracetic acid (from Example B₁) ethyl acetate.

Conditions for the Dehydration:

Example C

Pressure: 250 Torr; Head Temperature: about 42°C.
Sump temperature: 55–60°C.
At 25–30% peracetic acid in ethyl acetate.

What is claimed is:

1. A process for the production of water free solutions of percarboxylic acids having two to four carbon atoms comprising extracting the aqueous solution of the percarboxylic acid with a tertiary phosphate ester having three to 30 carbon atoms and desorbing the extract with a solvent for said percarboxylic acid selected from the group consisting of hydrocarbyl alkanoates having four to 10 carbon atoms, chlorinated aliphatic hydrocarbons and aromatic hydrocarbons, said solvent boiling lower than said phosphate ester.

2. A process according to claim 1 wherein the percarboxylic acid is a peralkanoic acid and the phosphate has the formula

where R₁, R₂ and R₃ are alkyl, aryl or aralkyl.

3. A process according to claim 2 including the additional step of removing the final amount of water from the desorbate by azeotropic distillation with a hydrocarbyl alkanoate having four to 10 carbon atoms boiling below the percarboxylic acid.

4. A process according to claim 3 wherein the desorbing solvent boils above the percarboxylic acid.

5. A process according to claim 3 wherein the desorbing solvent boils below the percarboxylic acid.

6. A process according to claim 2 wherein the percarboxylic acid is peracetic acid.

7. A process according to claim 2 wherein the aqueous percarboxylic acid solution contains 10 to 80 percent of percarboxylic acid.

8. A process according to claim 7 wherein the phosphate ester is trimethyl phosphate, tributyl phosphate or trioctyl phosphate.

9. A process according to claim 7 wherein the desorption is carried out with a hydrocarbyl alkanoate having four to 10 carbon atoms.

10. A process according to claim 9 wherein the hydrocarbyl alkanoate is an alkyl alkanoate.

11. A process according to claim 9 wherein the hydrocarbyl alkanoate is an alkyl alkanoate or cyclohexyl alkanoate.

12. A process according to claim 2 including the additional step of removing the final amount of water from the desorbate by azeotropic distillation with an alkyl alkanoate having four to 10 carbon atoms boiling below the percarboxylic acid.

13. A process according to claim 2 wherein the solvent is an alkyl acetate having four to 10 carbon atoms.

14. A process according to claim 13 wherein the alkyl acetate is n-butyl acetate.

15. A process according to claim 13 wherein the alkyl acetate is ethyl acetate.

16. A process according to claim 2, wherein the solvent is selected from the group consisting of ethyl acetate, propyl acetate, butyl acetate, amyl acetate, 2-ethyl-hexyl acetate, cyclohexyl acetate, t-butyl acetate, isoamyl acetate, propyl formate, butyl formate, methyl propionate, ethyl propionate, methyl butyrate, ethyl butyrate, methyl valerate, sec. hexyl acetate, propyl propionate, butyl propionate, amyl propionate, methyl isobutyrate, ethyl valerate, propyl isovalerate, methyl caproate, methyl pivalate, ethyl pivalate, propyl pivalate, isopropyl pivalate, butyl pivalate, sec.-butyl pivalate, amyl pivalate, carbon tetrachloride, chloroform, ethylene dichloride, acetylene tetrachloride, ethylene trichloride, 1,2-dichloroethylene, benzene, toluene, xylenes and ethyl benzene.
